UNITED STATES PATENT OFFICE.

OSCAR J. ZIEGLER, OF FREEPORT, ILLINOIS, ASSIGNOR TO THE STOVER
MANUFACTURING COMPANY, OF SAME PLACE.

DESIGN FOR A BASE FOR WINDMILL-HEADS.

SPECIFICATION forming part of Design No. 26,870, dated April 6, 1897.

Application filed May 15, 1895. Serial No. 549,446. Term of patent 14 years.

To all whom it may concern:

Be it known that I, OSCAR J. ZIEGLER, a citizen of the United States, and a resident of Freeport, in the county of Stephenson and State of Illinois, have invented and produced a new and original Design for a Base for Windmill-Heads, of which the following is a full, clear, and exact description.

The leading feature of my design consists in a base for a windmill-head having an elongated opening in the upper portion thereof.

The drawing shows the base of a windmill-

head embodying my design, in which drawing—

A is the base, and B is the elongated opening in the upper portion thereof.

What I claim is—

The design for the base for a windmill-head, substantially as herein shown and described.

OSCAR J. ZIEGLER.
